UNITED STATES PATENT OFFICE

2,343,968

PELT OR CASE FORM

John J. Fitzgerald, Cheyenne, Wyo.

Application November 25, 1942, Serial No. 466,902

3 Claims. (Cl. 45—24)

This invention relates to an adjustable pelt or case form, and has for the primary object the provision of a device of this character on which a pelt or case may be easily and quickly arranged and which will properly shape and prevent the pelt or case from shrinking without unduly subjecting the pelt or case to stretching action during the drying thereof.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a front elevation, illustrating an adjustable pelt or case form constructed in accordance with my invention.

Figure 2 is a sectional view taken on the line 2—2 of Figure 1.

Figure 3 is a sectional view taken on the line 3—3 of Figure 1.

Referring in detail to the drawing, the pelt or case form consists primarily of a frame 5 and a sustaining means 6 therefor. The frame 5 is made from a single length of manually bendable metallic stock and includes rod-like members 7 and a substantially V-shaped connecting portion 8 which may be employed to facilitate the insertion of the frame in a pelt or case. The free ends of the members 7 are bent at right angles and arranged in opposed relation to form stops 9 to prevent the sustaining means from accidentally moving off the frame. The stock of the frame is manually bendable in order that the frame may be shaped to fit pelts varying in size and for pelts wherein the front and rear quarters thereof vary in size from each other. For instance, the members 7 may be bent toward and from each other adjacent to their formation with the connecting portion 8 to compensate for the difference in size of the front quarter of the pelt to the rear quarter. The sustaining means 6 is employed for maintaining the members 7 at a desired distance apart after they have been made to fit a pelt having known measurements.

The sustaining means 6 include substantially rectangular shaped plates 10 and 11. The plate 10 is bent to form guide flanges 12 at opposite longitudinal edges thereof to slidably receive the plate 11. One end of the plate 10 is rolled or bent upon itself to form a barrel 13, having the free end of the material of the plate arranged

under the flanges 12. The barrel 13 slidably receives one of the members 7 with a frictional fit and has formed thereon a tine 14. One end of the plate 11 is bent or rolled upon itself to form a barrel 15 which slidably receives with a frictional fit the other member 7 of the frame. A tine 17 is formed on the barrel 15.

Ears 16 are formed on the plate 11 and are bent over the edges thereof to overlie the free bent end of said plate 11 for maintaining said end in the barrel shape.

The plate 10 is apertured and the plate 11 has a slot 19, said aperture of the plate 10 and slot 19 receive a bolt 18 having a wing nut 20 threaded thereon providing a releasable securing means between the plates 10 and 11 whereby they may be adjusted endwise of each other for the purpose of permitting the members 7 to be moved toward and from each other for the adjustment of the frame as above specified.

To use the present invention, a pelt is selected and the measurements as to its front and rear quarters are determined. The members 7 of the frame 5, with the wing nut backed partly off the bolt, are then bent to approximately fit the known measurements of the pelt and said frame is then inserted into the pelt from the rear end thereof using the connecting portion 8 to facilitate the insertion of the frame in the pelt. The front legs of the pelt are arranged at one side of the frame and the tines 14 and 17 are inserted through the rear legs. The sustaining means 6 is then slid on the members 7 toward the stops 9 to bring about a desired tautness of the pelt on the frame and the wing nut is tightened on the bolt securing the sustaining means so that the members 7 of the frame 5 will be maintained a proper distance apart for the pelt on the frame so that during the curing of the pelt it will be kept from shrinking and be free from strain from undue stretching effect thereon.

The sustaining means 6 is held from sliding accidentally on the members 7 by frictional engagement therewith. Whenever the friction needs to be increased, due to wear or otherwise, the barrels 13 and 15 may be pinched with pliers or a similar tool. It is preferable to pinch the barrel 13 by applying the tool on the ends of the flanges 12 adjacent to said barrel 13 and to pinch the barrel 15 by applying the tool to the ears 16 and plate 11 which lie close to said barrel 15. The pinching or contracting of the barrels 13 and 15 is made while the barrels are on the members 7.

From the foregoing description, taken in con-

nection with the drawing, it will be seen that a very efficient, durable and compact form has been provided which may have a pelt easily and quickly applied thereon and will shape the pelt without undue stretching thereof during the drying or curing of the pelt. Due to the simplicity in construction of this device, it may be economically manufactured and sold at a low cost.

While I have shown and described the preferred embodiment of my invention, it will be understood that minor changes in construction, combination and arrangement of parts may be made without departing from the spirit and scope of the invention as claimed.

Having thus described my invention, what I claim is:

1. In a pelt or case form, a manually bendable elongated frame including spaced members and a substantially V-shaped connecting portion integral therewith, plates slidably engaged with each other and having ends rolled to form barrels slidably receiving said members with frictional fit, and means for adjustably connecting said plates.

2. In a pelt or case form, an elongated frame

including spaced members and a substantially V-shaped connecting portion integral therewith, said members being bendable toward and from each other, plates slidably engaged with each other and having ends rolled to form barrels slidably receiving the members with frictional fit, guide flanges formed on one of said plates slidably receiving the other plate, and a fastener adjustably connecting said plates, and tines formed on the barrels of said plates.

3. In a pelt or case form, an elongated frame including spaced members and a substantially V-shaped connecting portion integral therewith, said members being bendable toward and from each other, plates slidably engaged with each other and having ends rolled to form barrels slidably receiving the members with frictional fit, guide flanges formed on one of said plates slidably receiving the other plate, a fastener adjustably connecting said plates, tines formed on the barrels of said plates, said members having the free ends thereof bent at right angles and arranged in substantially opposed relation to form stops.
